UNITED STATES PATENT OFFICE.

WILLIAM L. WALKER, OF BOSTON, MASSACHUSETTS.

SUBMARINE.

1,177,157.

Specification of Letters Patent. Patented Mar. 28, 1916.

Application filed November 12, 1915. Serial No. 61,057.

To all whom it may concern:

Be it known that I, WILLIAM L. WALKER, a citizen of the United States, and resident of Boston, in the county of Suffolk and State of Massachusetts, have invented new and useful Improvements in Submarines, of which the following is a specification.

This invention relates to submarine boats, and its object is to provide means automatically to control the depth to which the boat shall descend in order to avoid the risk of injury in striking the bottom or from hydrostatic pressure encountered at too great a depth, this object being attained by the provision of means, automatically to create buoyancy at any depth without the release of weights or other external devices.

A further object is to provide means for raising a sunken submarine to the surface in the event that she has been sunk but is uninjured, by striking the bottom or by the hydrostatic pressure, this object being attained by the provision of means, adapted to be operated by the crew, to create a large amount of reserve buoyancy without the employment of any of the stored or inclosed air supply which is or may be essential to the preservation of life within the boat.

The invention is applicable to submarines that rise and sink at will without any fore and aft inclination of the axis of the boat, but is peculiarly applicable to those submarines which dive at an angle for the reason that these boats may plunge their noses into the bottom when diving in shallow water or may get beyond control of the operators and descend into dangerous depths.

The invention is also peculiarly applicable to those boats the form of whose cross section departs from the circular cross section commonly employed, because this form of hull has not the natural strength to resist external pressure possessed by a hull with circular cross sections; they therefore cannot be safely submerged to as great a depth as boats of the former type. In both types it is essential that the safe submergent depth shall not be exceeded.

Referring to the drawings which illustrate certain embodiments of my invention,—Figure 1 is a vertical transverse section of a submarine illustrating an embodiment of my invention as applied to the auxiliary ballast or trimming tanks; and Fig. 2 is a similar view, partly in section and partly in elevation, illustrating an embodi-

ment of my invention as applied to the main ballast tanks.

Referring to Fig. 1: A is a main ballast tank of usual construction, open to see water as usual, with proper vents. B is an auxiliary ballast or trimming tank also of usual construction, filled or partly filled with water, and having a valve-controlled outlet normally closed by a valve C which opens outwardly and is held to its seat by a spring D surrounding the valve stem D'. E is a gas tight container or casing, the walls of which are capable of withstanding the maximum hydrostatic pressure which the hull withstands, and provided with a removable cover E'. The said container is adapted to hold a chemical F, such as calcium carbide or carbide of magnesium, adapted when brought in contact with water quickly to generate a gas. Upon a wall of the container having an aperture E² there is mounted a head G which has a central opening screw-threaded to receive one end of a pipe H, the other end of said pipe being connected to the main ballast tank A. The opposite or inner end of said head is provided with an annular recess G' internally screw-threaded to receive a diaphragm or barrier I of metal or other suitable material adapted to be perforated or broken at a predetermined pressure of water. Preferably a sprayer such as a perforated plate J is located between the diaphragm and the end of the pipe H mounted in said head. The pipe H has a check valve H' and a normally open gate valve H².

K is a cylinder provided with a piston K' having a piston rod K² surrounded by a spring K³, the tension of which is regulated by an adjusting nut K⁵ screwed into the end of the cylinder and into which the rod K² passes. The cylinder K is connected with the container E by a pipe L, and with the tank B by a pipe L' which communicates with a port K⁶ in the cylinder. Normally the spring K³ holds the piston against the front end of the cylinder with which the pipe L connects as shown, so that the port K⁶ is normally behind the piston. Preferably the piston is cut away as at K⁷, so that when the parts are in their normal position shown in the drawings, air is free to pass from the tank B through pipe L' and port K⁶ into the cylinder and out through the ports K⁸ provided for that purpose in the nut K⁵. A pipe M having a check valve M'

and a gate valve M^2 connects the container E and main ballast tank A.

The operation is as follows: If it is desired to limit the submergence of a submarine to a predetermined depth, a diaphragm I is placed in position which will resist a hydrostatic pressure less than that encountered at the predetermined depth. When the submarine in diving reaches a depth where the hydrostatic pressure is in excess of the strength of the diaphragm, the latter is immediately broken or ruptured and the water in the tank A enters the container E, comes in contact with the chemical F and quickly generates a gas which, flowing through the pipe L forces back the piston K' so that the port K⁶ is open, permitting the gas to flow through pipe L' into the tank B, and forcing the water from said tank, thus increasing the buoyancy of the boat and arresting further downward movement. If the auxiliary or trimming tank is located at or near the bow the forcing of the water therefrom in the manner above described and the consequent increase of buoyancy tends to change the direction of diving.

As soon as the fact of the rupture or breaking of the diaphragm becomes known, the gate valve H² in pipe H is closed and the contents of the container E forced through the pipe M into the tank A by any suitable means, as for example, a high pressure pump. The cover E' is then removed, a new diaphragm I placed in position, and the container reloaded with the chemical. The cover is thereupon replaced, and the device is again ready for use.

Under certain conditions it may be desirable to provide means not only for expelling water from an auxiliary or trimming tank or tanks as above described, but also from a main ballast tank or tanks. Where such is desirable, the boat may be provided with the construction shown in Fig. 2. In said figure, A is a main ballast tank of usual construction, open to sea water as usual, with proper vents, and located in such position in the boat that when the water is expelled or partly expelled therefrom, the submarine will be given greater buoyancy and further downward movement arrested. Upon a wall of said tank A there is mounted a valve N, preferably a gate valve, the outlet of which communicates with a port A' in said wall, and preferably a strainer S is provided at said outlet opening. The inlet end of said valve is provided with a nipple O internally screw threaded at O', to which is removably secured the gas tight container or casing E, the walls of which are capable of withstanding the maximum hydrostatic pressure which the hull withstands, one of said walls, as E', being removably secured to form a cover. The said container is adapted to hold the chemical

F, such as calcium carbide or carbide of magnesium, adapted when brought in contact with water quickly to generate a gas. Between the inlet of said valve N and said container E is the diaphragm or barrier I of metal or other suitable material adapted to be perforated or broken at a predetermined pressure of water. Preferably a pipe R provided with a check valve R' and gate valve R² connects said tank A and container E. Preferably also a sprayer, such as a perforated plate J, is located between the diaphragm I and the container, so that water entering said container through the valve, as hereinafter described, will be in the form of a spray.

When the submarine in diving reaches a depth where the hydrostatic pressure is in excess of the strength of the diaphragm, the latter is immediately broken or perforated permitting the sea water in the tank A to rush into the container E and come in contact with the chemical, forming a gas as above described, which immediately expels water from the tank A, increasing the buoyancy of the boat and arresting further downward movement.

The apparatus shown in Fig. 2 is also adapted for raising a submarine which has sunk but still retains a tight and undamaged hull. For this purpose, the construction is the same as that already described, but in addition a pipe U having a suitable check valve U' and gate valve U² is provided by which water may be pumped from the container into the main ballast tank by a high pressure pump or other suitable means. Suppose now the submarine has sunk to the bottom, rupturing the diaphragm I so that there is as the boat rests upon the bottom, water in the container E and some gas in the tank, but insufficient in volume to expel water in sufficient quantities to provide the necessary buoyancy to raise the boat. To raise the boat, the valve N is closed and the water and residue of the chemical in the container is pumped out. The wall or cover of the container is then removed, the chemical F placed within the container, and the removable cover replaced. The valve N is then opened permitting the water to rush in to form a gas as above described, thus expelling a quantity of water from the tank. If the amount of water thus expelled is insufficient to provide the necessary buoyancy to raise the boat, the above described operation can be repeated until sufficient buoyancy is obtained to accomplish the desired result. The chemical F is comparatively heavy and the residue remaining in the container E after the formation of the gas is also comparatively heavy. Therefore, when said residue is forced out of the container E, as above described, a very considerable weight is removed from

the boat thus aiding in the attainment of buoyancy.

It will be clear that diaphragm I of any desired strength corresponding to the desired depth may be employed, and it will also be clear that when once the diaphragm I is placed in operative position, it performs its function of permitting the water to come in contact with the chemical automatically, so that it is impossible for a negligent or adventurous operator to permit a submarine to descend into dangerous depths. In the embodiments of my invention herein described I have shown a diaphragm adapted 15 to be broken or ruptured at a predetermined hydrostatic pressure. This diaphragm is illustrative only and other means adapted to open in response to a predetermined hydrostatic pressure may be substituted for 20 said diaphragm without departing from my invention.

The invention above described is applicable to submarines of the type now in common use, and provides simple and effective 25 means not only for preventing accidents attributable to descents beyond a safe depth, but also for raising a sunken submarine without employment of the stored or reserved air supply.

30 I claim:

1. In a submarine, a container in normally closed communication with the sea water, a water tank, a passage between the container and tank, means opening in response to water pressure to admit water to the container, and material in the container adapted on admixture with water to generate a gas to expel water from said tank.

2. In a submarine, a container in normally closed communication with the sea water, a water tank, a passage between the container and tank, material in said container adapted on admixture with water to generate a gas to expel water from said tank, and means to force the contents of the container remaining after the formation of said gas out of the submarine.

3. In a submarine, the combination with a water ballast tank, of a container, means 50 between said tank and said container opening in response to water pressure to admit water to the container, and material in said container adapted on admixture with water to generate a gas to expel water from said tank.

4. In a submarine, the combination with a water ballast tank, of a container, a diaphragm between said tank and said con-

tainer adapted to be perforated by hydrostatic pressure to admit water into the said container, and material in said container adapted on admixture with water to generate a gas to expel water from said tank. 60

5. In a submarine, the combination with a water ballast tank, of a valve mounted on said tank, a container, a diaphragm between said container and the inlet of said valve adapted to be perforated by hydrostatic pressure to admit water into the said container, and material in said container adapted 65 on admixture with water to generate a gas to expel water from said tank. 70

6. In a submarine, the combination with a water ballast tank, of a normally open valve mounted on said tank, means to close 75 said valve, a container, a diaphragm between said container and the inlet of said valve adapted to be perforated by hydrostatic pressure to admit water into the said container, and material in said container adapted 80 on admixture with water to generate a gas to expel water from said tank.

7. In a submarine, the combination with a water ballast tank, of a valve mounted on said tank, a container having a removable 85 wall, a diaphragm between said container and the inlet of said valve adapted to be perforated by hydrostatic pressure to admit water into the said container, and material in said container adapted on admixture with 90 water to generate a gas to expel water from said tank.

8. In a submarine, the combination with a water ballast tank, of a valve mounted on said tank, a container removably secured on 95 said valve, a diaphragm between said container and the inlet of said valve adapted to be perforated by hydrostatic pressure to admit water into the said container, and material in said container adapted on admixture 100 with water to generate a gas to expel water from said tank.

9. In a submarine, the combination with a water ballast tank, of a container, a normally closed passage between said tank and 105 said container, material in said container adapted on admixture with water to generate a gas to expel water from said tank, and a pipe connecting said container and said tank and having a check valve, whereby 110 the contents of said container may be forced into said tank.

Signed by me at Boston, Massachusetts, this ninth day of November, 1915.

WILLIAM L. WALKER.
